Specification for Design.

Patented Oct. 8, 1912.

Application filed August 23, 1911. Serial No. 645,662. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Berth-Lamp Fixtures, of which the following is a specification.

The nature of my design is fully illustrated in the accompanying drawing, to which reference is made and in which,

Figure 1 represents a front elevation of the design; and Fig. 2 a side elevation thereof.

My design comprises a flat upright base portion having a convex projecting portion or hood at the upper portion of the base portion, the sides of the convex portion extending downwardly and merging into the base portion.

I claim:

The ornamental design for a berth lamp fixture as shown and described.

LINDSLEY SCHEPMOES.
